UNITED STATES PATENT OFFICE

WILBUR E. SANDERS, OF MUNCIE, INDIANA, ASSIGNOR TO GENERAL MOTORS CORPORATION, OF DETROIT, MICHIGAN, A CORPORATION OF DELAWARE

ROTARY VALVE FURNACE

Application filed August 12, 1929. Serial No. 385,133.

This invention relates to the treatment of metals and particularly to an improvement in apparatus for acting on a bar of stock to bring it in proper condition for a forming operation. The apparatus constituting the present subject matter was especially designed for use in the manufacture of poppet valves of the type employed in internal combustion engines and for convenience of dis-
10 closure, the invention will be hereinafter described with reference to such use, although it may be employed for other purposes, as will be obvious.

Poppet valves comprising a head and a stem may be made according to different methods, but the method with which this invention is concerned consists of bringing one end of a bar or rod of suitable stock, cut to predetermined size, to a desired heat
15 for the proper working, and then subjecting the heated end to pressure to upset or form a button or head on the portion that was not exposed to the heat. To provide an improved furnace construction for heating the bar
20 stock prior to the upsetting operation is one of the primary objects of the present invention.

A further object is to provide an improved type of furnace structure which will be more
25 or less automatic in the operation and into which the stock may be introduced, carried through and then discharged at the end of the treatment in condition for the action thereon of a bulldozer or press.

Another and important object of the invention is to provide a cooling system for maintaining cold that portion of the stock which will later be the stem of the valve and which is not to be upset.

Other objects and features of advantage will become apparent in the course of the following specification when taken in connection with the accompanying drawings, illustrating a preferred embodiment of the
45 invention.

In the drawings

Fig. 1 is a top plan view of the furnace forming the present subject matter with parts broken away and shown in section.

Fig. 2 is a sectional view taken on line

2—2 of Fig. 1 and Fig. 3 is a detail sectional view taken on line 3—3 of Fig. 1.

Referring to the drawings, the reference characters 1—1 indicate a number of I-beam sections making up a supporting frame for the furnace structure, and 2 indicates an annular furnace constructed of fire brick or other suitable refractory material and providing a circular heating chamber 3. The bottom wall of the heating chamber consists of a hollow rotor or conveyor 4 preferably made by joining two concave rings of material such as boiler plate, edge to edge, having its top surface covered by suitable refractory material 5, and provided with a series of cylindrical sleeves or locators 6 extending therethrough and affording a number of vertical openings to receive the rods or stock, indicated at 7, to be treated. The rotor is supported by a ring 8 which also supports an annular trough 9 carrying sand or the like, and into which projects the flange 10 of a ring of T-shape in section carried on the under side of the innermost wall of the furnace, to constitute a heat seal. At suitable intervals the ring 8 is provided with a series of dependent L-shaped legs or feet 12 preferably supported resiliently, as by means of hold-down bolts 13 and coil springs 14, upon a ring or carrier 15. The carrier 15 rests upon and is rotated by a number of drive wheels or rolls, only two of which are shown in the drawings. The roll 17 is keyed or fixed on the shaft 18 supported in suitable bearings upon the framing and has keyed at one end the bevel gear 19 for driving engagement with a ring gear 20 pivoted on a vertical shaft 21, while the roll 22 is fixed on a shaft 23 and driven by a bevel gear 28 meshing with the ring gear 20. At the opposite end of the shaft 18 suitable drive mechanism therefor is provided, which may be housed in the casings 26 and operated from any convenient source of power, whereby the rotor or conveyor 4 is continuously operated counter-clockwise through the furnace to carry the bar stock therethrough.

The lower end of each bar rests upon and is supported by a ring or skid 30 adjustably supported as through set screws 31 by frame

brackets 32, whereby upon adjustment of the set screws the ring may be raised or lowered to expose a predetermined length of the upper portion of the bar to the heat of the furnace chamber. At one portion of its extent the skid 30 may be cut away or provided with an opening 33 through which the bars may drop when they are brought over the opening by the conveyor, into a trough or chute 34, preferably leading to the bulldozer or upsetting machine. Located just beyond the discharge point is a loading platform where the bars may be inserted either automatically or by hand into the sleeves 6 of the conveyor. At the loading platform the furnace chamber is closed by the walls 36 and 37 of suitable refractory material, the wall 37 having a slot or opening 38 for the passage of the upper portion of the bar into the heating chamber.

Heat may be supplied to the furnace chamber in any of a number of ways but it will probably be found preferable in most instances to employ a series of oil-burning nozzles such as indicated at 40, each in alignment with an opening or passageway 41 through the outer wall of the furnace. For supplying fuel to the burners 40, use may be made of three rotary blowers 42, 43 and 44. As shown in the drawings, the blower 42 is connected through a conduit 45 with a manifold 46, leading to fifteen of the burners 40 supplying substantially one-half of the furnace chamber with heat, while the blower 43 is connected by the conduit 47 and manifold 48 with eight of the burners and the blower 44 is connected by the conduit 49 and manifold 50 with seven of the burners, the last two blowers supplying fuel to heat that portion of the furnace chamber through which the stock moves as it nears the end of its treatment in the furnace. It will be noted, therefore, that the greater portion of the heat will be supplied to the bar after it has covered substantially half its travel through the furnace and that the application of heat at the entrance is gradual.

Along the axis of turning movement of the rotary conveyor 4 are located two vertically extending concentric pipes 54 and 55 carried by and rotatable with the conveyor, the pipe 54 being connected by a flexible joint 56 with a conduit 57 leading from a suitable source of water or other cooling medium under pressure and being connected at its lower end by the radially extending conduit 58 with the interior of the hollow conveyor, while the bottom of the other pipe 55 is placed in communication with the hollow conveyor at another point through the conduit 59. This allows circulation of the cooling water supplied under pressure, through the hollow conveyor, to maintain the lower portion of the stock outside the heating chamber relatively cool while the upper portion is being

heated for the upsetting operation. The cooling fluid that returns to the outermost pipe 55 rises therein and overflows at its top into a tank or tub 60 having a discharge pipe 61 leading to a sewer or other suitable place of disposal. Because of the relative movement between the rotary pipe 55 and stationary overflow tank 60, the bottom of the overflow tank is provided with an upstanding tubular wall 62 surrounding the pipe 55 and the upper portion of the pipe 55 is flared outwardly and reversely bent as at 63 across and beyond the upper portion of the tube 62.

From the above description it will be apparent that there is provided a construction wherein heat will be applied to substantially half the length of the bar stock or that portion to be upset to form the valve head, and wherein, due to the resistance of the water cooled back of the bottom wall, the heat is evenly distributed over the exposed portion within the furnace chamber, while the part entered into and below the water back remains comparatively cold. With this method of heating, uniform scale is obtained from the heated end of the bar to the end of heat.

Although the foregoing description has been more or less specific, the invention is not limited to the exact details referred to, and it is to be understood that such modifications can be made as come within the scope of appended claims.

I claim:

1. Heat treating apparatus including a chambered furnace, a movable conveyor for carrying articles through the furnace and constituting one wall of the furnace chamber, and embodying refrigerating means so arranged that portions of the article positioned adjacent thereto are maintained cool while other portions extending into the furnace are heated.

2. Heat treating apparatus, including a chambered furnace, a chambered conveyor device movable through the furnace chamber, and adapted to carry an article so that a portion projects into the furnace chamber and means to circulate cooling fluid through said chambered device for maintaining cool that portion of the article adjacent thereto.

3. Heat treating apparatus, including a chambered furnace, a conveyor movable through the furnace chamber and having therein a passageway for cooling medium, a skid for supporting an article to be treated that extends loosely through an opening in the conveyor and therebeyond into the furnace chamber, and means to introduce cooling medium into the passageway in said conveyor for maintaining relatively cool the portion of the article outside the furnace chamber.

4. Heat treating apparatus, including an annular chambered furnace, a rotary hollow conveyor movable through the furnace chamber and having a series of vertical openings

therein for the projection therethrough of articles to be treated, an annular stationary skid below the conveyor with which the lower portions of the articles have sliding engagement and by which they are supported so that their upper portions extend above the conveyor and into the furnace chamber, means for circulating cooling medium through the hollow conveyor to maintain the lower portions of the articles relatively cool, and adjustable means for regulating the height of the skid to subject predetermined portions of the articles to the heat treatment.

5. In addition to the elements of claim 4, a rotatable supporting ring for the conveyor, and resilient connections between the ring and conveyor.

6. The structure of claim 9, wherein the rotary hollow conveyor forms the bottom wall 20 of the furnace chamber and has its upper surface covered with refractory material.

7. Heat treating apparatus, including an annular chambered furnace, a rotary hollow conveyor for carrying articles through the 25 furnace chamber, provided with openings through which portions of the articles project, and means to circulate cooling medium through said hollow conveyor.

8. The apparatus of claim 7, wherein the 30 circulating means includes a pair of concentric pipes rotatable along the rotary axis of the conveyor, and having connections with the interior of the hollow conveyor at spaced apart points, means to connect the innermost 35 pipe with a source of cooling medium under pressure, a stationary tub having an upstanding tubular portion surrounding the upper portion of the outermost pipe, and a reversely bent annular end portion on said outermost 40 pipe extending across and beyond the top edge of the upstanding tubular portion, whereby the cooling medium overflows from the outermost rotary pipe into the stationary tub.

45 9. Heat treating apparatus, including an annular chambered furnace, a rotary hollow conveyor movable through the furnace chamber and having a series of vertical openings therein for the projection therethrough of articles to be treated, an annular stationary skid below the conveyor with which the lower portions of the articles have sliding engagement and by which they are supported so that their upper portions extend above the conveyor and into the furnace chamber, and means for circulating cooling medium through the hollow conveyor to maintain the lower portions of the articles relatively cool.

In testimony whereof I affix my signature.

WILBUR E. SANDERS.
